Primary Examiner — Kendra Leslie Hamilton*Assistant Examiner* — Michael Hoffman(74) *Attorney, Agent, or Firm* — Birchwood IP(57) **CLAIM**

The ornamental design for a breast pump heating base, as shown and described.

DESCRIPTION

FIG. 1 is a front, left and top perspective view of a breast pump heating base, showing my new design;

FIG. 2 is a rear, right and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is a perspective view of the breast pump heating base, shown in a condition of use.

The broken lines in the drawings depict portions of the breast pump heating base that form no part of the claimed design. The broken lines showing a breast pump in FIG. 9 depict environmental structure that forms no part of the claimed design. All broken lines form no part of the claim. The dot-dash broken lines depict the boundaries of the enlargements that form no part of the claimed design.
